CLAIM

The ornamental design for blanket with pockets for chemical heating pads, as shown and described.

DESCRIPTION

FIG. 1 is front elevational view of a blanket with pockets for chemical heating pads showing my new design;

FIG. 2 is a rear elevational view thereof;

FIG. 3 is left side elevational view thereof;

FIG. 4 is a right elevational view thereof;

FIG. 5 is a top plan view thereof;

FIG. 6 is a bottom plan view thereof; and,

FIG. 7 is an isometric view showing my design.

The cross-hatched shading is fragmentally shown for convenience of illustration, it being understood that the cross-hatched shading is uniformly continued over the surfaces on which it appears.

The elements shown in broken lines represent stitching as part of the invention.
